UNITED STATES PATENT OFFICE.

CHARLES OLIVER FOLTZ, OF CHICAGO, ILLINOIS.

DESIGN FOR A MATCH-LIGHTER.

SPECIFICATION forming part of Design No. 33,495, dated November 6, 1900.

Application filed July 18, 1900. Serial No. 24,110. Term of patent 14 years.

To all whom it may concern:

Be it known that I, CHARLES OLIVER FOLTZ, a citizen of the United States, and a resident of Chicago, in the county of Cook and State 5 of Illinois, have invented and produced a new and original Design for a Match-Lighter, of which the following is a full, clear, and exact specification.

In the drawings, Figure 1 is a side edge view of a match-lighter, showing my new design. Fig. 2 is a perspective view of the same

My design embraces the entire match-lighter; and it consists of a single triangular-shaped strip A of metal having its ends b b

meet at a point intersected by a plane at right angles to its central portion c, in which latter an opening d is made. The inside opposing surfaces of the ends of the strip are provided with protuberances e e, which project toward each other.

What I claim as new, and desire to secure by Letters Patent, is—

The design for a match-lighter as herein shown and described.

CHARLES OLIVER FOLTZ.
